LOCKING CLOSURE CONSTRUCTION

Thrasybule D. Lazarides, New York, N. Y.

Original application April 4, 1930, Serial No. 441,488, now Patent No. 1,926,204, dated September 12, 1933. Divided and this application February 6, 1933, Serial No. 655,329

10 Claims. (CL. 70—90)

This invention relates to a locking closure construction of the type which is adapted to be applied to the opening in a tank or other container.

5 The closure is particularly adapted to be applied to the usual gasoline tanks of automobiles. Such tanks usually have a neck projecting from the body of the tank, and the rim of the neck has suitably spaced openings therein to receive tabs or projections or finger pieces which are fastened to the closure cap. The locking mechanism which will hereafter be described is provided on an adapter sleeve and is adapted to block one or more of the openings in the rim of 10 the sleeve so that when the lock is in locked position one or more of the finger pieces of the cap cannot register with the openings in the rim of the adapter sleeve with the result that the cap cannot be removed from the container 15 until the lock is unlocked.

One object of this invention is the provision of an adapter sleeve provided with a locking mechanism and with means for securely attaching the same to the neck of a container.

25 Another object of this invention is the provision of a washer for preventing relative rotary movement between the parts and a securing bar for preventing relative axial movement of the parts.

30 Other objects and features of the invention will more fully appear from the following claims, taken in conjunction with the description and accompanying drawing, which, however, are to be considered as merely illustrating and in no way limiting the invention to the embodiment 35 shown and described.

In the drawing:

Fig. 1 represents a vertical section through the closure shown in Fig. 2, looking squarely into the locking mechanism;

40 Fig. 2 represents a horizontal section taken through Fig. 1.

Fig. 3 represents a plan view showing the interior of the cap to be applied to the adapter sleeve.

45 Fig. 4 represents a view partly in section and partly in elevation, of a form of the device in which the lock is applied to an adapter for the neck of the container; and

50 Fig. 5 represents an exploded view showing the washer which is applied between the neck of the container and the adapter sleeve.

55 Referring now to the drawing, only such parts of the container have been shown as is necessary to illustrate the manner in which the closure is applied thereto. The neck of the container is

denoted by the numeral 1, the rim is denoted by the numeral 2, and the openings in the rim are denoted by the numeral 3. Only two openings have been shown but it is to be understood that any number of such openings, which are necessary to receive a corresponding number of finger pieces on the cap, may be used.

5 The locking closure has been particularly designed so that the lock is on the side thereof rather than on the top. In order to obviate the necessity of having to alter the neck 1 of the container, an adapter 4 is used. In its operation the adapter is really a continuation of the neck of the container. The adapter is fastened to the neck of the container by any suitable means, such as a locking washer 6 and a retaining bar 8. The locking washer and the retaining bar are designed so that the adapter may be applied easily and quickly to the necks of the usual tanks without altering the necks in any way. The locking washer is first placed on the rim 2 of the container and the tabs 10 are bent down so as to engage the sides of the openings 3 which are in the rim 2. The adapter is then placed on top of the washer 6 so that the under-turned end 12 of the locking bar passes through one of the openings 3. The adapter is then turned so that the under-turned end 12 of the locking bar 8 passes under the rim 2 of the container and until the slots 14 are directly above the tabs 16 so that the tabs 16 can be bent upwardly to fit into the slots 14. Preferably the tabs 16 are in pairs so that there is a projection 18 between each pair of tabs and against which the sides of the tabs fit quite closely. If desired, the lower portion of the adapter may be cut away, as is indicated at 20, to facilitate the application of the adapter to the container and the use of the tabs 16. The locking bar 8 is rigidly fastened in any suitable manner, for instance, by screws 22, on the top of the lower flange of the adapter.

A compressible washer 24 is preferably used to make a liquid tight connection between the bottom of the adapter and the locking washer 6. It will thus be readily understood that the adapter is held on the rim 2 by the under-turned end 12 of the locking bar 8, and that the adapter is prevented from being turned, so that it cannot be removed from the container, by the down-turned tabs 10 which prevent the locking washer 6 from turning on the rim 2 and the up-turned tabs 16 which prevent the adapter from being turned on the locking washer 6.

The top of the adapter is provided with a rim 26 having openings 28, the rim and openings cor-

responding to the rim 2 and the openings 3 of the container, so that the same cap 30 having the same finger pieces 32, which was used on the rim 2, can be used on the rim 26. It is of course possible to make the rim 26 and the openings 28 in such a way that a special cap will have to be used but the rim and the openings are preferably such that the original cap can be used.

10 The locking mechanism which prevents the cap from being removed from the adapter, includes a locking plate 34 which may move in such a manner that the block 36 enters one of the openings 28. The block 36 prevents the fingers from registering with the opening 28 and consequently will prevent any of the other fingers which are affixed to the cap from registering in their openings. The block 36 is preferably a part of the locking plate 34 which is preferably curved to 15 fit the inside of the adapter and is slidably fastened to the wall of the adapter by the fastening pins or rivets 38 which pass through slots 40 in the plate 34 so that the plate can slide up and down to bring the block 36 either into the opening 28 or sufficiently below the rim 26 to permit the fingers 32 to pass over the top of the block 36 and pass out of the openings 28 when the cap is to be removed from the container. The locking plate 34 is moved into either its locked 20 or unlocked position by the pin 42 which is operated from the barrel 44 of the lock, a slot 46 being provided in the plate 34 to permit the necessary side movement of the pin 42 as the lock revolves. The lock barrel 44 which is shown is intended to be operated by a key, although it 25 may be operated by any other means such as are usually used with similar locks.

The cap 30 is locked on the rim of the adapter (which may be considered as the rim of the container) when the parts are in the position shown 40 in Fig. 1. In order to remove the cap, the key is inserted in the lock barrel 44 and is turned, which operation moves the pin 42 downwardly. The movement of the pin 42 pulls downwardly the locking plate 34 and the block 36, whereupon the cap may be removed by twisting it until the finger pieces 32 register with the openings 28, whereupon the cap may be pulled directly off of the adapter.

50 The locks which are used are preferably such that the locking operation is completed and the key can be withdrawn at a half revolution of the key so that the lock may remain in unlocked position in order that the cap may be used as an ordinary cap when desired and does not necessarily have to be locked on the container. Thus, during the day the lock may remain in unlocked position so that the cap may easily be removed for filling the tank, but at night, when the car is 55 in a public garage, the lock may be locked to prevent access to the tank. However, the lock may be such that the key cannot be withdrawn from the lock except when the lock is in locked position whereby the cap must always be locked on the tank.

This application is filed as a division of my application for Locking closure, Ser. No. 441,488, filed April 4, 1930, which has become Patent No. 1,926,204, dated September 12, 1933.

70 From the above description it is apparent that various modifications of the invention may be made and it is therefore to be understood that, although a particular and preferred form of the invention has been described, it is recognized that 75 many other and further modifications may be

made and it is desired that the invention be construed as broadly as the claims, taken in conjunction with the prior art, may allow.

What I claim is:

1. A locking closure adapted to be applied to a neck of a container having openings in the neck, including a cap, fingers on the cap adapted to pass through the openings in the neck, and a locking mechanism adapted to block at least one of the openings to prevent one of the fingers from registering with the openings until the locking mechanism is unlocked to unblock the opening. 10

2. In a combination of the character described, an adapter sleeve, means whereby said sleeve may be secured to a neck of a container, said means including a washer provided with means for preventing relative rotary movement between said sleeve and the container, and means for preventing relative axial movement between said sleeve 15 and the container. 20

3. A device of the character described, which includes, an adapter sleeve, means whereby said sleeve may be attached to a neck of a container, said means including a washer having tabs adapted to be bent downwardly over the edges of the openings in the neck of the container, a rim on said adapter and provided with a slot, a tab on said washer and adapted to be bent upwardly to be received by said slot, said washer with its bent tabs preventing relative rotary movement 25 of the parts, and means for preventing relative axial movement of the parts and unauthorized removal of said sleeve. 30

4. A device of the character described which includes, an adapter sleeve, means for attaching said sleeve to a neck of a container, said means including a washer having tabs adapted to be bent over the edges of the openings in the neck of the container, a lower rim on said adapter and provided with a slot, a tab on said washer adapted to be received by said slot, said means also including a retaining bar extending under said lower rim for preventing unauthorized removal of said sleeve from the neck of the container. 35

5. A device of the character described which includes, an adapter sleeve, means for attaching said sleeve to a neck of a container, said means including a washer having tabs adapted to be bent over the edges of the openings in the neck of the container, a lower rim on said adapter and provided with a slot, a tab on said washer adapted to be received by said slot, said means also including a retaining bar extending under said lower rim for preventing unauthorized removal of said sleeve from the neck of the container, said lower 55 rim being provided with a compressible washer for preventing leakage from the container. 60

6. A device of the character described, which includes, an elongated neck on a container, the upper portion of said neck being provided with 65 openings, a cap member for said neck, said cap member being provided with fingers adapted to be received by said openings in said neck, a locking plate slidably mounted on said neck, said locking plate being provided with a block adapted to enter one of said openings in said neck, a key operated locking mechanism on said neck, and means whereby movement of said locking mechanism by a key moves said locking plate so that said block enters one of said openings in said neck and prevents removal of said fingers on said cap. 70

7. A device of the character described, which includes, an elongated neck on a container, the upper rim of said neck being provided with 75

spaced openings, a locking plate slidably mounted on said neck, said locking plate being provided with blocking means adapted to enter one of said rim openings on said neck, and a locking mechanism associated with said locking plate for moving said blocking means into one of said rim openings in said neck.

8. A device of the character described, including in combination, an elongated neck on a container, the rim portion of the neck being provided with spaced openings, a cap member for said neck and provided with fingers adapted to be received by said rim openings in said neck and locking means on said neck cooperating with one of said rim openings for preventing removal of said fingers on said cap member.

9. A device of the character described including in combination, an elongated neck on a con-

tainer, the rim portion of the neck being provided with spaced openings, a cap member for said neck and provided with fingers adapted to be received by said rim openings on said neck, and locking means carried by said neck and adapted when operated to block one of the rim openings in said cap member for preventing removal of the said fingers on said cap member.

10. A device of the character described, including, in combination, an elongated neck on a container and having a plurality of spaced openings in its upper rim adapted to receive a cover or cap member, and locking means on said neck adapted when operated to enter and block one of said rim openings in said neck and prevent removal of a cover or cap member.
